UNITED STATES PATENT OFFICE.

FRANK R. WOOD, OF NEW YORK, N. Y.

CAP HOLDER AND SUPPORT.

Application filed April 8, 1922. Serial No. 550,698.

To all whom it may concern:

Be it known that I, FRANK R. Wood, a citizen of the United States, residing at New York, in the county of New York and State of New York, have invented certain new and useful Improvements in Cap Holders and Supports, of which the following is a specification.

This invention relates to a combined top retaining and tooth paste tube holding device and particularly adapted for retaining the removable cap when the same is removed from the tube preliminary to using the contents thereof.

The primary object of the invention is the provision of a tooth paste cap holding device which acts in the nature of a hinge thus preventing the cap from being lost when the same is removed, and at the same time provides a means for holding and supporting the tooth paste tube from a nail or screw, or similar device.

Another and very important object of the invention is the provision of a combined hinge and support for a tooth paste tube which may be constructed of a single piece of wire and bent in the form of a loop and also engaging the neck of the removable cap yet permitting the same to be removed from the tube and swung on its pivot whereby the tooth paste may be forced through the neck of the tube ready for use.

With these and other objects in view the invention consists in the construction and novel combination of parts hereinafter fully described, illustrated in the accompanying drawings, and pointed out in the subject matter being claimed, it being understood that various changes in the form, proportion, size and minor details of construction may be resorted to without departing from the spirit and scope of the invention.

In the drawings, Figure 1 is a perspective view showing the invention as applied on a conventional tooth paste tube and removable cap thereon.

Figure 2 is a plan view.

Figure 3 is a similar view to that shown by Figure 1, showing the cap removed.

Figure 4 is a side view of the device removed from the cap.

Referring now to the drawings, wherein like reference characters designate corresponding parts throughout the several views, 5 designates the conventional type of collapsible tooth paste tube having the usual

neck 6 which may be threaded or otherwise constructed to receive the threaded cap 7 thereon in the manner well understood.

The invention proper consists of a single strip of wire bent in the form of a loop 8 so as to be suspended from a nail 9 or screw from a wall or support so that the front face of the tube is presented to view and when the tube is so supported might be considered in the nature of an advertising feature since it is otherwise customary to conceal the tube or otherwise place the same in a cabinet or holder. It will be observed that the eye 8 is in substantial parallelism with the body of the tube so that the same is suspended vertically. The wire of the said loop is twisted about as shown at 10 and loosely encircles the groove 11 of the removable cap so that said cap may be rotated and unscrewed from the neck of the tube. The arms 13, 14 of the loop or bail 15 are preferably crossed as shown at 17 and terminate in inwardly extending front ends 18 which may be snapped in the aperture of the raised knuckle 19 preferably formed integral with the top of the collapsible tube. It will thus be seen that by simply pressing the arms 13, 14 inwardly the end or hooks 18 will be separated sufficient to permit the same to enter the apertures in the ends of the said knuckle so that the said bail may be properly secured. In this position it will be readily recognized that when the cap 7 is removed, or rotated, the said cap may be swung outwardly to the dotted line position as shown by Figure 3, consequently permitting the tooth paste to be forced out of the tube and thus it will be apparent that the cap is maintained at all times and is prevented from being lost as is otherwise the case.

The particular feature however, to be emphasized in this type of a cap retaining device is that not only does the cap holder act in the nature of a hinge but by reason of constructing the loop in the manner shown, the entire tube may be readily supported on a nail or hook, for instance, and thus the simple device performs a useful and double function as heretofore set forth, as well as presenting the highest regard for sanitation and cleanliness.

While I am aware that the broad idea of providing means for retaining a cap on a tooth paste tube has been attempted before, my particular invention is directed more to the combined feature of a cap retaining and

a tooth paste tube supporting device so constructed of a single strip of wire that the same may be readily bent and attached to any type of tooth paste tube having a convenient form of attaching means for the ends of the bent wire.

While I have illustrated and described my invention with some degree of particularity, I realize that in practice various alterations 10 therein may be made. I therefore reserve the right and privilege of changing the form of the details of construction or otherwise altering the arrangement of the correlated parts without departing from the spirit of 15 the invention or the scope of the appended claims.

Having thus described my invention, what I claim as new and desire to secure by United States Letters Patent is:—

20 1. A combined cap holder and container supporting device comprising a strip of wire, bent to form a closed loop, the ends of the

loop being twisted about each other, the continuation of said twisted portion of the wire being bent in opposite directions, forming a bail adapted to encircle a removable cap, and the free ends of the wire being attached to the body of a container to form a hinged connection for said cap.

2. A combined cap holder and container 30 supporting device comprising a strip of wire bent to form a closed loop, the ends of the loop being twisted about each other and disposed at right angles to the loop, the continuation of said twisted portion of the wire 35 being bent and curved outwardly in opposite directions forming a bail and adapted to encircle a removable cap, and the free ends of the wire being crossed and attached to the body of the container to form a hinged 40 connection for said cap.

In testimony whereof I affix my signature.

FRANK R. WOOD. [L.S.]
